PACKAGING

George M. Danenbauer, Chicago, Ill., assignor, by
mesne assignments, to The Diamond Match
Company, New York, N. Y., a corporation of
Delaware

Application February 14, 1946, Serial No. 647,530

2 Claims. (Cl. 93—3)

1

This invention relates to dispensing cartons and more particularly to cartons of the type containing rolls of paper such as wax paper which dispense the paper in web form, which paper may be torn from the dispensed web in pieces of desired lengths against a cutting edge secured to the carton.

Prior to the instant invention, wax paper dispensing cartons have been made of cardboard blanks folded into the shape of a rectangular parallelepiped in which the structure comprises a tray for receiving the roll of wax paper and a top portion, which top portion includes a front flap.

In some prior boxes the web is dispensed between the front flap which is disposed inwardly of the tray and the front of the tray. As the web is dispensed the tendency is to pull the roll entirely out of the tray causing the roll to fall on the floor which, of course, would be unsanitary, and it is necessary to hold the top in place with one hand while the web is pulled with the other hand. Further, the roll may fall out of the box if the box is dropped inadvertently.

In other prior constructions, the top portion comprises a fold line intermediate the front and back of the top portion, which fold line extends from one small side of the carton to the other small side and the rear portion of the top back of the fold line is fastened to the small sides or ends of the carton in such a manner that when the top is opened it provides an opening which is smaller than the diameter of the roll to be dispensed. Such prior constructions involve a weakened top and after continued folding of the top the tendency is to tear that portion of the top which is attached to the sides which, when torn, results in a failure of the box to function in the manner desired.

Still another prior construction involves the use of cylindrical bearings secured to the inner faces of the small end walls of the carton or tray which bearings extend within the core of the roll to be dispensed. Such cylindrical bearings are difficult to incorporate in a wax paper box dispenser and the resulting construction is expensive to manufacture. Further, in constructions of this type the wax paper roll can not be loaded into the box after the box is assembled.

It is an object of the instant invention to provide a relatively simple box construction which may be readily manufactured, conveniently used and from which the roll can not be readily displaced accidentally such as when the box is dropped or when it is inverted.

It is another object of the invention to provide

2

a wax paper dispenser which will dispense paper smoothly and conveniently from a roll.

It is a further object of the instant invention to teach a method of folding a wax paper carton from a blank and loading same with a roll of wax paper.

It is still a further object of the instant invention to provide a novel wax paper carton dispenser blank from which the carton may be made by folding same.

Other objects and the nature and advantages of the instant invention will be apparent from the following description taken in conjunction with the accompanying drawings, wherein:

15 Fig. 1 is a view in perspective of a carton in accordance with the instant invention with the front flap thereof on the outside of the carton and with the piece which covers the finger grip opening unremoved from the carton;

20 Fig. 2 is a view similar to Fig. 7 with the top of the carton raised to expose the roll therein and with the piece which covers the finger grip opening removed;

25 Fig. 3 is a view partly in front elevation and partly in vertical section with the front flap disposed on the inside of the carton behind the web of material to be dispensed;

Fig. 4 is a transverse vertical section taken at right angles to the view shown in Fig. 3; and

30 Fig. 5 is a plan view of a blank from which the carton is made.

Referring to the drawings, the blank 10, see Fig. 5, comprises a front section 11, a bottom section 12, a back section 13, a top section 14, and a front flap 15. The sides 16 of the carton, see Figs. 1 and 2, are made up of the rectangular tabs 17 which project from the front section 11, the trapezoidal tabs 18 which extend from the bottom section 12, and the rectangular tabs 19 which extend from the back section 13. Extending from the bottom of the rectangular tabs 17 are the rectangular flaps 17' which are separated from the rectangular tabs 17 by the fold lines 17''. Extending upwardly from the rectangular tabs 19 are the spindle bearing portions 20 provided with circular holes 20' as shown in Fig. 5 on the carton blank 10.

A finger grip opening in the carton may extend into the top section 14 and front flap 15 which opening may be temporarily closed by the piece 21 which is held to the top section 14 by a space between the perforations as shown, and the portion of the piece 21 which extends within the flap 15 may be completely severed therefrom. The cutter edge element 22 may be of

metal secured to the top 31 of the front section 11.

The score line 23 provides for convenient folding of the front section 11 and bottom section 12 so that the front section 11 and the bottom section 12 may be arranged in planes at right angles to each other. The score line 24 between the bottom section 12 and the back section 13 provides for convenient folding of these sections so that they may be arranged in planes at right angles to each other. The score line 25 between the top section 14 and the back 13 provide a convenient hinge between the top and the back. The score line 26 provides a convenient hinge between the top section 14 and the front flap 15. The spindle bearing portions 20 are adapted to be laid over on the inside of the tabs 19 in the form of the easy curved section 27, as shown in the upper left-hand portion of Fig. 3. The score lines 28 provide a convenient fold line between the tabs 19 and the back section 13. The score lines 29 provide a convenient fold line between the trapezoidal tabs 18 and the bottom section 12. The score lines 30 provide a convenient fold line between the rectangular tabs 17 and the front section 11.

In the complete assembly, the tabs 17 form the outer lamina of each of the sides 16, the tabs 18 form the intermediate lamina of each of the sides 16, and the tabs 19 form the inner lamina of each of the sides 16. The tabs 17, 18 and 19 in the assembly may be suitably fastened together with adhesive or by the use of staples or the like, and it is obvious that when the tabs 17, 18 and 19 are laminated as shown in section in Fig. 3, a tray-like structure, as shown in Fig. 2, will result with the top section 14 formed integral with the back 13 with a hinge line at 25 as shown in Fig. 2. The spindle bearing portions 20 which are arranged as shown in section in Fig. 3 have the openings 20' associated with the extreme ends of the core 32 of the wax paper roll 33 in a manner such that the ends of the core 32 are journaled for rotation within the openings 20' of the spindle bearing portions 20. As shown in Fig. 3, the ends of the core 32 extend beyond the ends of the roll of wax paper 33.

The roll of wax paper 33, including the core 32, is adapted to be loaded within the dispensing carton either through the top opening or through the end. When the box is to be loaded through the top, the box is assembled as described and the roll inserted through the top opening into the position shown in Fig. 3, and the ends of the core 32 will automatically slip into the position with respect to the openings 20' in the spindle bearing portions 20 as shown in Fig. 3.

When the box is to be loaded through the end, the blank shown in Fig. 5 is first folded along score lines 23, 24, 25, and 26 and the flap 15 is then secured to the front section 11 either on the inside of the front section 11 or on the outside by glueing or by the use of a conventional tongue and slit arrangement. The roll 33 is then inserted through one of the open ends or sides. Then the spindle bearing portions 20 are turned over on the inside of the carton to take the position shown in Fig. 3 and the tabs 17, 18, and 19 are folded along score lines 28, 29 and 30 and the side 16 assembled by lamination as already described above and the rectangular flaps 17' which are folded along line 17'' to take the position shown in Fig. 3 complete the assembly.

The user may open the box as shown in Fig. 3, remove the piece 21 and then insert the flap 15 behind the started web as shown in Fig. 4. The web may then be pulled out to the desired length and torn across the cutter edge 22. Thereafter, the web may again be started by inserting a finger through the opening formed by the removal of the piece 21 and pulling a short length of web upwardly so as to expose same. As lengths of web are pulled from the roll, the roll revolves with the exposed ends of the core 32 within the openings 20' of the spindle bearing portions 20 smoothly and the dispensing operation is facilitated without concern regarding the possibility of the roll being pulled entirely out of the box as the spindle bearing portions 20 hold the roll securely within the box while the dispensing operation progresses. Even when the box is inverted with the top 14 open, the roll will not fall out of the box and, accordingly, the user need have no concern about the roll falling on the floor and becoming unsanitary.

It will be obvious to those skilled in the art that various changes may be made without departing from the spirit of the invention and therefore the invention is not limited to what is shown in the drawings and described in the specification but only as indicated in the appended claims.

I claim:

30 1. The method of folding and loading a package in the shape of a rectangular parallelepiped having a front, bottom, back, top, and two sides, comprising folding a blank into the shape of a tube having a rectangular cross section which may be opened along a line on the surface of the tube parallel to the axis of said tube, inserting a roll of sheet material having a core completely into said tube through one open end thereof, forming a portion of the ends on each side of said tube as a bearing for the core of said roll, and folding the ends of said tube across the core of said roll of said sheet material to form the sides of said package and engaging the bearings with each end of the core of said roll.

45 2. The method of folding and loading a package in the shape of a rectangular parallelepiped having a front, bottom, back, top, and two sides, comprising folding a blank into the shape of a tube having a rectangular cross section which may be opened along a line on the surface of the tube parallel to the axis of said tube, forming a pierced portion of the ends on each side of said tube in a continuous curve as a bearing for the core of a roll of sheet material to be loaded into said package, and folding the ends of said tube at right angles to the axis thereof to form the sides of said package with each bearing extending from one margin of each of the sides of said tube into the tube, inserting a roll of sheet material and having a core into said tube through the opening and engaging each side of the core of said roll with the corresponding bearing.

GEORGE M. DANENBAUER.
